Primary Examiner — George D Kirschbaum

(57) **CLAIM**

The ornamental design for a 3D-sliding spherical puzzle-toy, as shown and described.

DESCRIPTION

The patent or application file contains at least one drawing executed in color. Copies of this patent or patent application publication with color drawing(s) will be provided by the Office upon request and payment of the necessary fee.

1. 3D-sliding spherical puzzle-toy

1.1 is a top view.

1.2 is a bottom view.

1.3 is a left perspective view.

1.4 is a right perspective view.

1.5 is a second left perspective view.

1.6 is a second right perspective view.
